UNITED STATES PATENT OFFICE.

FRANK D. LEA, OF FINDLAY, OHIO.

PIANO-LIFTING TRUCK.

1,328,634.

Specification of Letters Patent. Patented Jan. 20, 1920.

Application filed April 2, 1919. Serial No. 287,021.

To all whom it may concern:

Be it known that I, FRANK D. LEA, a citizen of the United States, residing at Findlay, in the county of Hancock and State of Ohio, have invented certain new and useful Improvements in Piano-Lifting Trucks, of which the following is a specification.

This invention comprises an improved construction of piano lifting truck of the type shown in U. S. patents of Raynor No. 616,972 and No. 667,575, of which patents I am the owner and under which patents I have manufactured piano lifting trucks.

The primary objects of my invention have been to simplify the construction of the truck as disclosed particularly by the later of the two patents above mentioned, to provide a somewhat different arrangement and

structure for the lever lifting device affording a construction of greater strength and one more easily manufactured than that proposed by said patent, to improve in details the means for limiting the movement of the handles and for holding said handles flat against the truck when not in use, and to correspondingly improve the pawl mechanism for locking the roller against movement.

With the foregoing and other objects in view, a full understanding of my improved device will be had on reference to the following detailed description, and to the accompanying drawings in which—

Figure 1 is a perspective view of one of my trucks, showing the handles projecting therefrom as when susceptible of being used, and illustrating the lever bail in a position midway of its extremities of movement, as 40 in the act of elevating the frame of the truck relatively to the roller;

Fig. 2 is a rear elevation of the device, parts arranged with handles folded;

Fig. 3 is a section on the line 3—3 of Fig. 1.

Fig. 4 is a sectional view showing more clearly the connection between the lifting slides and frame of the truck, on the line 4—4 of Fig. 2; and

Fig. 5 is a detail section on the line 5—5 of Fig. 2.

In view of the disclosure in the patents previously identified, it is unnecessary to indicate herein with much detail the mode of use of my lifting truck. It suffices to state that two trucks comprising a set are

usually employed for facilitating the moving of the piano to be transported. The trucks are suitably attached to opposite ends of the piano by straps or any suitable means, 60 the frame of each truck being equipped with supporting feet or arms to be engaged beneath the piano, after which the lifting device of each truck may be operated to elevate the frame and cause the weight of the 65 piano to be received upon the roller forming a part of said lifting device. When the piano is supported by the rollers of the respective trucks it is obviously easy to move. Again, when desired the piano may be 70 turned upon end with one of the trucks therebeneath and readily moved by reason of the provision of casters at the end of the truck opposite that equipped with the roller of the lifting device. 75

With the foregoing general provisions in mind, I will proceed to describe a single one of my trucks. The truck comprises a frame composed of end bars 1 equipped with pads 2, and side bars 3. On the side 80 of the upper end bar 1 opposite the pad 2 thereof, said end bar is provided with a pair of substantial casters 4. Crossed rods 5 connect the side bars 3 intermediate their ends and one of these rods 5 has slidable 85 thereon a clip 6 adapted to engage one of a pair of bracerods 7 by which the two handles 8 are connected together, said handles being pivotally connected with a cross rod 9 suitably attached to the side bars 3 90 of the frame. When the clip 6 engages the brace rod 7 with which it may coöperate, the handles 8 are held flat against the frame of the truck, the disposition which they take when not being used, as when a piano 95 is turned on end and supported by the roller 10, and casters 4 of the truck. To limit the movement of the handles 8, in an upward direction I use the stop and guide rods 11, the same being pivoted at 12 to brackets 100 13 attached to the side bars 3. At their free or outer ends the rods 11 are enlarged to provide stop extremities 11a.

The lifting device used by me for my truck is somewhat like that shown in Patent 105 No. 667,575 above mentioned, save that I have provided a more rigid and economically made construction and one which has a self-locking action as will now be pointed out.

Pivoted to the brackets 13 at the outermost portions thereof is a lever bail 14 of substantially U-form. The points of pivotal

connection of the lever 14, with the brackets 13, are located at the extremities of the sides of the lever. A short distance from said pivotal points the sides of the lever 14 5 are pivotally connected by links 15 with lifting slides 16 mounted on the side bars 3 of the truck frame. I have provided a specifically new means for connecting the slides 16 with the side bars 3, a means which 10 is especially advantageous from a viewpoint of assemblage of the parts. Secured to each slide 16 is a U-shaped guide bracket and the two brackets 17 are connected by a cross plate 18, the fastening between the parts 15 being designated 19. The space between the sides of each bracket 17 opens outwardly, so to speak and the rear side of the lower end bar 1 is recessed or cut away at two points adjacent to the bars 3, as shown at 20, to 20 permit relative movement of the brackets 17 and the side bars 3 incident to the raising of the truck frame by the lifting slides 16, when the lever or bail 14 is pulled outward and downward. The relation of the pivotal 25 connections between the parts 13, 14, and 15 is such that when the lever or bail 14 is pulled outward from the frame of the truck and forced downward until practically engaged with the lower portions of the side 30 bars 3, said lever is locked against outward movement by the weight supported by the truck. This is due to the shifting of the pivotal connections between the lever 14 and links 15 nearer to the bars 3 than are the 35 pivotal connections between lever 14 and the brackets 13.

In order that the lever 14 may be held against accidental displacement when in its uppermost position, a spring catch 21 is 40 secured to the upper end bar 1 and arranged to engage the cross bar of the lever 14 as shown in Fig. 1.

It will be understood that the lifting feet 22 of the truck frame are turned laterally 45 from the lower ends of the bars 3 as proposed in Patent No. 667,575. The pawl mechanism at present used by me to lock the roller 10 from turning, comprises the pawl 23 actuated by the spring plate 24 so that it 50 has a normal tendency to engage notches 25 of the roller 10. I provide a release lever 26 for the pawl, pivoted to the cross plate 18 at 27, said release lever having a projection 28 near its free end to engage in a 55 recess 29 in the adjacent slide 16 whereby to interlock the lever 26 in a position in which it engages the pawl 23 and maintains the latter inoperative.

A keeper 30 at the outer side of the free 60 end of the lever 26 is attached to the cross plate 18 and limits the movement of said lever. The upper edge of the release lever 26 at the point where it is adapted to engage between the plate 18 and pawl 23 is 65 beveled to facilitate wedging of the lever

between the said parts for disengaging the pawl. The said bevel also tends to cause a slight lateral movement of the lever 26 to effect interlocking of the projection 28 in the recess 29.

It will be noted from the foregoing that I have devised a construction for my truck wherein I may employ almost exclusively round metal such as rods or flat strap metal, also malleable or steel castings, in the economical construction of my device. Practically the only castings employed by me are the lifting slides 16 which have journals for the roller 10. I might note also that the stop and guide rods 11 pass through eyes 31 forming the ends of a cross rod 32 carried by the handles at the upper sides of the latter. The specific method of use of my truck will be self evident to those versed in the art from the foregoing disclosure of the detail features. I might note, however, that the rod 32 has a rotative connection with the handles 8 being journaled after a manner between the outer sides of the handles and strap plates by which the handles are mounted on the pivoted cross rod 9. Thus it is that owing to the manner in which the stop and guide rods 11 pass through or interlock with the eyes 31 of the rod 32, said rod is adapted to turn approximately a quarter revolution incident to the movement of the handles through an arc of approximately 90° representing the extent of movement of said handles.

Having thus described my invention, what I claim as new is:—

1. In a lifting truck of the class described, the combination with a frame comprising side and end bars, of lifting means for said frame consisting of lifting slides mounted on the side bars of the frame, a roller supported by the lower ends of said lifting slides and instrumentalities for effecting a relative movement of the lifting slides and the frame including a lever bail having the sides thereof pivoted at their inner extremities to the side bars of the frame, links pivotally connected with the sides of the lever bail intermediate the ends of said bail, connections between the links and the lifting slides, means for positively connecting the lifting slides with the side bars comprising a cross plate attached to said lifting slides, and connecting and guiding brackets also secured to said lifting slides and engaging with the side bars of the truck frame for sliding action relatively thereto, the lower end bar of the truck frame being cut away at one side to form clearance recesses permitting the relative movement of the guide brackets and side bars aforesaid.

2. In a lifting truck of the class described, the combination with a truck frame, of a lifting device carried thereby and comprising a roller adapted to support said frame,

together with means for effecting relative movement of the frame and roller, lifting feet carried by the frame to engage with a piano or the like, handles pivotally connected with the frame at one side thereof, brace rods connecting the side bars of the frame, a rod connecting the handles together, and a clip mounted on one of the brace rods aforesaid and engageable with the handle connecting rod for holding the handles against movement under certain conditions of use of the truck.

3. In a lifting truck of the class described, the combination with a truck frame, of a lifting device mounted thereon and comprising a roller adapted to support said frame, together with means for effecting relative bodily movement of the frame upward respecting said roller, the frame being

equipped with suitable lifting feet, and lock 20 means for preventing turning of the roller consisting of a pawl, a cross plate secured to the lower portion of said frame and supporting said pawl, spring means tending to cause engagement of the pawl with the 25 roller, a release lever pivoted to said cross plate and having an upper beveled edge portion to wedge between the pawl and cross plate as the lever is moved to effect disengagement of the pawl from the roller, 30 and interlocking means between the release lever and an adjacent portion of the lifting device for holding the release lever in a position maintaining the pawl disengaged from said roller. 35

In testimony whereof I affix my signature.

FRANK D. LEA.
